Primary Examiner — Paula Allen Greene(74) *Attorney, Agent, or Firm* — David W. Carstens;
Carstens, Allen & Gourley, LLP(57) **CLAIM**

The ornamental design for a teardrop urn, as shown and described.

DESCRIPTION

FIG. 1 is a front view of a teardrop urn;
 FIG. 2 is a rear view of a teardrop urn;
 FIG. 3 is an upper perspective view of a teardrop urn;
 FIG. 4 is a lower perspective view of a teardrop urn;
 FIG. 5 is a right side view of a teardrop urn;
 FIG. 6 is a left side view of a teardrop urn;
 FIG. 7 is a top view of a teardrop urn; and,
 FIG. 8 is a bottom view of a teardrop urn.
 The broken lines depict portions of the teardrop urn that form no part of the claimed design.

1 Claim, 8 Drawing Sheets(56)
